AUTOMATIC BACKGROUND CONTROL

Randall C. Ballard, Audubon, N. J., assignor to
 Radio Corporation of America, a corporation of
 Delaware

Application April 4, 1939, Serial No. 265,922

4 Claims. (Cl. 178—7.5)

My invention relates to direct current reinserting circuits and particularly to television receivers of the type in which the background or average over-all illumination of the received picture is controlled automatically.

In British Patent 422,906 there is described a television receiver circuit for reinserting the direct current component of the picture signal at the cathode ray tube and thereby controlling the picture background, this circuit comprising a diode circuit connected across the input circuit of the cathode ray tube. It has been found that while this circuit functions satisfactorily to provide automatic background control, it tends to reduce the high frequency response of the system at the control grid of the cathode ray tube. This is because the diode capacity is connected across the cathode ray tube input electrodes and, therefore, adds to the cathode ray tube input capacity.

It is, accordingly, an object of my invention to provide an improved automatic background control circuit for a television receiver.

It is a further object of my invention to overcome at least partially the above-mentioned undesirable feature of an automatic background control or D. C. inserting circuit wherein a diode or the like is connected between the last video amplifier and the cathode ray tube.

It is a still further object of my invention to provide an improved D. C. inserting means for either a television transmitter or television receiver.

In practicing my invention, use is made of inductance coils which act to increase the high frequency response both because they resonate a portion of the circuit at a frequency falling just beyond the high frequency end of the desired pass band or otherwise peak the high frequency response and because they isolate the diode capacity from the cathode ray tube input capacity. The invention may also be considered from the standpoint of filter theory, the inductance coils and tube capacities forming a low pass filter, one coil of which is separating the diode capacity from the cathode ray tube capacity. Strictly speaking, however, filter theory is not followed since it is undesirable to add any capacities to those necessarily present even though the terminating impedances may not be correct from a filter standpoint.

The invention will be better understood from the following description taken in connection with the accompanying drawing in which the single figure is a circuit diagram of a portion of a television receiver embodying my invention.

Referring to the drawing, there is shown the last video amplifier tube at 10 which may be a pentode provided with self-bias by means of a cathode resistor 11 and shunting condenser 12.

5 The cathode ray tube shown at 13 may be of a well known type comprising a cathode 14, a control grid 15, a first anode 17, a second anode 18 and the usual fluorescent screen 19.

The coupling between the plate of the amplifier 10 and the control grid of the cathode ray tube 13 is through an inductance coil 21 and a coupling condenser 22. An operating voltage is applied to the plate of tube 10 through a plate resistor 23 and a second inductance coil 24. Each of the coils 21 and 24 preferably is shunted by a damping resistor.

10 The direct current inserting circuit comprises a rectifier such as a diode 26 having its cathode connected to the lower end of coil 24 through a condenser 27 and having its plate connected to ground. The diode 26 is shunted by a resistor 28.

15 As will be described hereinafter, a D. C. potential which is a measure of the picture background appears at the cathode of diode 26. This potential is applied to the cathode ray tube grid 16 through a resistor 31.

20 The amount of steady bias on the control grid 15 may be adjusted manually by means of a variable tap 32 on a potentiometer resistor 33. A large bypass condenser 34 holds the cathode 14 at ground potential at the picture frequencies.

25 From an inspection of the drawing, it will be apparent that the capacity of the diode 26 indicated at 36 is not in parallel with the input capacity of the cathode ray tube 13 indicated at 37 since these two capacities are separated by the coil 24. The D. C. connection of the diode 26 to the control grid 16, of course, does not place the diode capacity directly across the cathode ray tube input circuit because of the high resistance grid leak resistor 31 in the circuit.

30 The action of the diode circuit in providing automatic background control is as described in the above-mentioned patent. Briefly, it is as follows: The composite signal comprising both picture signal and synchronizing impulses is applied to the input circuit of amplifier 10 with such polarity that the synchronizing impulses are negative at the cathode of diode 26. At the transmitter these impulses have been made always to go to "black" or to some other fixed level. The synchronizing impulses cause pulses of current to flow through the diode periodically to charge up the condenser 27. By giving resistor 28 a high resistance value, the time constant of the dis-

charge circuit for condenser 27 is made so large that the condenser 27 discharges only slightly between successive horizontal or line synchronizing impulses whereby the D. C. voltage applied to the grid 16 is a measure of the height of the impulses and, therefore, a measure of the original picture background.

Referring again to the function of the coils 21 and 24, it will be noted that these coils, together with the output capacity 38 of the tube 10 and the tube capacities 36 and 37, are in the form of a low pass filter where the signal output for the cathode ray tube is taken off the first filter section and the output for the diode 26 is taken off the succeeding section. My circuit arrangement results in the cathode ray tube input capacity 37 being common to the two filter sections, which is desirable since it is larger than either the tube capacity 36 or 38. Thus the filter theory requirement that capacity 37 be twice capacity 38 and also twice capacity 36 is approximately fulfilled.

Disregarding filter theory, it will be noted that coil 21 is a series coil resonating with tube capacities 36 and 37 at a frequency higher than the high frequency end of the pass range, while coil 24 acts as a peaking coil for signals applied to the grid 16 in addition to providing separation of the capacities 36 and 37.

It has been found that the above-described circuit gives the desired automatic background control while making it possible to extend the high frequency end of the amplifier pass range to a point where the high frequency response of the receiver is satisfactory.

From the foregoing, it will be evident that the invention is not limited to television receivers, but is applicable to television transmitters or other apparatus where the tube 13 may be replaced by an amplifier tube.

I claim as my invention:

1. In combination, an electric discharge tube having a plate electrode, a second electric discharge tube having a control electrode, said plate electrode being coupled to said control electrode through an inductance coil and a coupling condenser connected in series in the order named, a second inductance coil and a plate resistor connected in series, said second coil being connected to the junction point of said first coil and said coupling condenser, a rectifier coupled through a second coupling condenser to receive the signal voltage appearing across said plate resistor only, a resistor connected in shunt to said rectifier, and a resistor connected between said control electrode and the junction point of said second coupling condenser and the resistor shunting said diode.

2. In a television receiver, an electric discharge tube having a plate electrode, a cathode ray tube having a control electrode, said plate electrode being coupled to said control electrode through an inductance coil and a coupling condenser connected in series in the order named, a second inductance coil and a plate resistor connected in series, said second coil being connected to the junction point of said first coil and said coupling condenser, a diode having a plate and a cathode, said diode being coupled to receive the signal voltage appearing across said plate resistor only, the cathode of said diode being connected to the plate end of said resistor through a second coupling condenser, a resistor connected in shunt to said diode, and a resistor connected between said control electrode and said cathode.

3. In a picture channel for carrying picture signals and periodically recurring impulses which are of greater amplitude than the picture signals, in combination, an electric discharge tube having a plate electrode, a second electric discharge tube having a control electrode, said plate electrode being coupled to said control electrode through an inductance coil and a coupling condenser connected in series in the order named, a second inductance coil and a plate resistor connected in series, said second coil being connected to the junction point of said first coil and said coupling condenser, rectifier means coupled to receive the signal voltage appearing across said plate resistor only for deriving a direct current potential which is a measure of the height of said impulses, and a resistor connected between said means and said control electrode for applying said direct current potential thereto.

4. In a television receiver for receiving picture signals and periodically recurring impulses which are of greater amplitude than the picture signals, in combination, an electric discharge tube having a plate electrode, a cathode ray tube having a control electrode, said plate electrode being coupled to said control electrode through an inductance coil and a coupling condenser connected in series in the order named, a second inductance coil and a plate resistor connected in series, said second coil being connected to the junction point of said first coil and said coupling condenser, means including a diode to receive the signal voltage coupled appearing across said plate resistor only for deriving a direct current potential which is a measure of the height of said impulses, and a resistor connected between said means and said control electrode for applying said direct current potential thereto.

RANDALL C. BALLARD.
